HARRY BONAT, OF NEW YORK, N. Y.

HAIR WAVING APPARATUS

Application filed August 2, 1930. Serial No. 472,552.

This invention relates to permanent waving apparatus of the type adapted particularly for the so-called "croquignole" wave.

In the application of the "croquignole" wave to hair, it is customary to employ a clamping device which grips a lock of hair closely adjacent to the scalp. The hair is wound then from the free ends upon a spindle which is mounted preferably upon the clamp and is held against reverse rotation by a co-operating ratchet and pawl on the spindle and clamp. The hair on the spindle is then wrapped with a textile material such as flannel, which may be moistened with a suitable lotion, and the spindle with the wrapping is enclosed in an electrical heating device whereby the heat which is necessary to secure the permanent wave is readily applied to the hair.

It is the object of the present invention to provide an improved clamp and spindle and to otherwise facilitate the waving operation as described. Another object of the invention is the provision of a clamp which is more readily manipulated and which holds the hair more securely, and an improved ratchet mechanism whereby the spindle is prevented from turning in the reverse direction when the hair is wound thereon, so that the hair may be maintained under suitable tension.

Other objects and advantages of the invention will be apparent as it is better understood by reference to the following specification and accompanying drawing, in which

Fig. 1 is an elevation of the clamp and the co-operating spindle;

Fig. 2 is a section on the line 2—2 of Fig. 1;

Fig. 3 is an end elevation of the device illustrated in Fig. 1;

Fig. 4 is an elevation of the clamp in open position;

Fig. 5 is a plan view of the clamp;

Fig. 6 is an enlarged section of one end of the spindle; and

Fig. 7 is a plan view of the clamp showing a different type of locking mechanism therefor.

Referring to the drawing, the clamp comprises preferably two metal strips 5 bent in

U-shape and secured by rivets 6 with spacers 7 so as to afford adequate air space between the two arms. The conduction of heat is thereby minimized and the scalp is protected. Additional insulation may be provided by securing strips 8 of suitable material such as felt to the lower sides of the strips 5. The two strips 5 are pivoted at one end on a transversely extending pin 9 to which one of the strips may be secured, for example by a rivet 10. By thus having the two strips 5 pivoted to swing about the pin 9 which extends transversely of the strips, the strips in operation will move out from the head and the possibility of the clamp becoming entangled in adjacent strands of hair or striking against the clamps which have been previously applied is avoided. The pin 9 may extend loosely through the other strip and may have a threaded end 11 to receive a nut 12 whereby the strips may be adjusted relatively to each other. Cushions 13 of any suitable resilient material such as rubber may be disposed between the strips 5 to grip the hair which is drawn through the clamp and held thereby when the device is adjusted. To permit locking and adjustment of the clamp, a pin 14 is pivotally secured, for example by a rivet 15, to one of the strips 5 and is adapted to engage a slot in the contiguous end of the other strip. The end of the pin is threaded to receive a nut 16. The pin 14 is adapted to be swung to the position indicated in dotted lines in Fig. 5, to release the strips 5 which may be opened then as indicated in Fig. 4, to release the hair. It will be noted that adjustment of the tension is provided at both ends of the device by means of the nuts 12 and 16.

The pin 9 at one end of the device supports a bracket 17 having a relatively large opening therein, while the pin 14 at the other end of the device supports a bracket 18 with a slot 19 of generally rectangular form. The two brackets are intended to receive a spindle 20 which is of circular cross-section and preferably of varying diameter, as indicated in Fig. 1 of the drawing. It is provided with a clamp 21 which grips the ends of the hair while the latter is wound on the spindle. At

- one end the spindle has a knob or other suitable device 22 whereby the spindle may be rotated with the fingers. The other end has a recess 23 in which a rotatable ratchet member 24 is slidably mounted. A spring 25 tends to force the ratchet member which is provided with teeth 26 outwardly against similar ratchet teeth 27 on a collar 28. The collar is held immovable in the end of the 10 spindle 20 by means of the pin 29 or other suitable fastening. The end of the ratchet member 24 is preferably squared at 30 to engage the slot 19 in the bracket 18. Thus when the spindle is mounted in the brackets 17 15 and 18 it may be rotated in one direction, the squared end 30 being held from rotation so that the ratchet teeth 26 and 27 slip past each other. The teeth, of course, prevent reverse rotation.
- 20 In the application of the device as described, a clamp comprising the strips 5 is adjusted adjacent the scalp and a lock of hair is drawn therethrough, after which the two strips forming the clamp are moved to the 25 position indicated in Fig. 5, the pin 14 being adjusted to the full line position in that figure. The nuts 12 and 16 are then adjusted to afford sufficient tension to hold the hair firmly. The ends of the hair are then secured to the spindle 20 by means of the clamp 21. The spindle is mounted in the brackets 17 and 18 and is rotated until the hair is wound on the spindle. The ratchet holds the spindle in the adjusted position with the 30 hair wound thereon. The operations incidental to waving as previously described may then be performed, after which the hair is released and subjected to such further treatment as may be necessary.
- 40 In Fig. 7, I have illustrated a slightly modified form of clamp which differs from the structure illustrated in the preceding figures only in respect to the locking device which holds the two strips forming the clamp 45 in closed position. As shown in the drawing, the two strips 31 and 32 are connected at one end by a pin 33 threaded at one end to receive a nut 34, one of the strips being loose on the pin to permit adjustment. At the other end 50 a pin 35 is pivotally connected at 36 to one of the strips and engages the slotted end of the other strip. A cam lever 37 is pivoted on a block 38 which is threadedly mounted on the end of the pin 33. The cam lever engages 55 a seat of suitable form in the contiguous strip and may be employed to lock the clamp. By turning the block on the threaded end of the pin, the clamp may be adjusted to give the desired tension.
- 60 The device as described is simple and effective and is adapted particularly to facilitate the arrangement of the hair and the securing thereof by the clamp and spindle.
- 65 Various changes may be made in the details of construction and arrangement of the

parts without departing from the invention or sacrificing any of the advantages thereof.

I claim:

1. Apparatus of the character described comprising a clamp composed of opposed strips pivotally connected at one end to permit swinging movement about a common axis, resilient means on the opposed edges of the strips, and means at opposite ends of the strips to afford relative adjustment thereof, 70 said axis of swinging movement of the strips being substantially perpendicular to the planes of the opposed edges of the strips.

2. Apparatus of the character described comprising a clamp composed of opposed strips pivotally connected at one end to permit swinging movement about a common axis, resilient means on the opposed edges of the strips, and means at opposite ends of the strips to afford relative adjustment 80 thereof, including a pin pivoted at the end of one of the strips and adapted to engage the end of the contiguous strip, said axis of swinging movement of the strips being substantially perpendicular to the planes of the 85 opposed edges of the strips.

3. Apparatus of the character described comprising a clamp composed of opposed strips pivotally connected at one end to permit swinging movement about a common axis, resilient means on the opposed edges of the strips, and means at opposite ends of the strips to afford relative adjustment thereof, 90 including a pin pivoted at the end of one of the strips and adapted to engage the end of the contiguous strip and adjustable clamping means on the end of the pin, said axis of swinging movement of the strips being substantially perpendicular to the planes of the 95 opposed edges of the strips.

4. Apparatus of the character described comprising a clamp composed of opposed strips pivotally connected at one end to permit swinging movement about a common axis, resilient means on the opposed edges of the strips, and means at opposite ends of the strips to afford relative adjustment thereof, 100 including a pin pivoted at the end of one of the strips and adapted to engage the end of the contiguous strip, and an adjustable cam lever on the end of the pin, said axis of swinging movement of the strips being substantially perpendicular to the planes of the 105 opposed edges of the strips.

5. Apparatus of the character described comprising a clamp composed of opposed strips pivotally connected at one end to permit swinging movement about a common axis, resilient means on the opposed edges 110 of the strips, and means at opposite ends of the strips to afford relative adjustment thereof, including a pin pivoted at the end of one of the strips and adapted to engage the end of the contiguous strip, and adjustable means 115 threadedly mounted on the end 120 of the pin, said axis of swinging movement of the strips being substantially perpendicular to the planes of the opposed edges of the strips.

125

- of the pin, said axis of swinging movement of the strips being substantially perpendicular to the planes of the opposed edges of the strips.
6. Apparatus of the character described comprising a clamp composed of opposed strips pivotally connected at one end to permit swinging movement about a common axis, resilient means on the opposed edges 10 of the strips, and means at opposite ends of the strips to afford relative adjustment thereof, including a pin pivoted at the end of one of the strips and adapted to engage the end of the contiguous strip, and an adjustable cam lever threadedly mounted on the end of the pin, said axis of swinging movement of the strips being substantially perpendicular to the planes of the opposed edges of the strips.
- 10 7. Apparatus of the character described comprising a clamp composed of opposed strips, bent in U shape with the arms secured in spaced relation, pivot means connecting the strip to permit swinging movement about a common axis, resilient means 20 on the opposed edges of the strip, and means at opposite ends of the strips to permit relative adjustment thereof, said axis of swinging movement of the strips being substantially perpendicular to the planes of the opposed edges of the strips.
- 20 8. Apparatus of the character described comprising a clamp composed of opposed strips, bent in U shape with the arms secured 30 in spaced relation, pivot means connecting the strip to permit swinging movement about a common axis, resilient means on the opposed edges of the strip, and means at opposite ends of the strips to permit relative adjustment thereof, including a pin pivoted at the end of one of the strips and adapted to engage the end of the contiguous strip, and an adjustable cam lever threadedly 40 mounted on the end of the pin, said axis of swinging movement of the strips being substantially perpendicular to the planes of the opposed edges of the strips.
- 30 9. Apparatus of the character described comprising a clamp composed of opposed strips, bent in U shape with the arms secured 50 in spaced relation, pivot means connecting the strip to permit swinging movement about a common axis, resilient means on the opposed edges of the strip, and means at opposite ends of the strips to permit relative adjustment thereof, including a pin pivoted at the end of one of the strips and adapted to engage the end of the contiguous strip, said axis of swinging movement of the strips being substantially perpendicular to the 55 planes of the opposed edges of the strips.
- 45 10. Apparatus of the character described comprising a clamp composed of opposed strips, bent in U shape with the arms secured 60 in spaced relation, pivot means connecting the strip to permit swinging movement about a common axis, resilient means on the opposed edges of the strip, and means at opposite ends of the strips to permit relative adjustment thereof, including a pin pivoted at the end of one of the strips and adapted to engage the end of the contiguous strip, and adjustable clamping means on the end of the pin, said axis of swinging movement of the strips being substantially perpendicular to the 65 planes of the opposed edges of the strips.
- 55 11. Apparatus of the character described comprising a clamp composed of opposed strips, bent in U shape with the arms secured 70 in spaced relation, pivot means connecting the strip to permit swinging movement about a common axis, resilient means on the opposed edges of the strip, and means at opposite ends of the strips to permit relative adjustment thereof, including a pin pivoted at the end of one of the strips and adapted to engage the end of the contiguous strip, and an adjustable cam lever on the end of the pin.
- 70 12. Apparatus of the character described comprising a clamp composed of opposed strips, bent in U shape with the arms secured 75 in spaced relation, pivot means connecting the strip to permit swinging movement about a common axis, resilient means on the opposed edges of the strip, and means at opposite ends of the strips to permit relative adjustment thereof, including a pin pivoted at the end of one of the strips and adapted to engage the end of the contiguous strip, and adjustable means threadedly 80 mounted on the end of the pin, said axis of swinging movement of the strips being substantially perpendicular to the planes of the opposed edges of the strips.
- 80 13. Apparatus of the character described comprising a clamp composed of opposed strips pivotally connected at one end to permit swinging movement about a common axis, means at opposite ends of the strips to afford relative adjustment thereof, resilient means on the opposed edges of the strips, brackets supported on the clamps, a spindle 85 having a rotatable end, the spindle and rotatable end resting respectively in the brackets, and means within the spindle to limit rotation of the end in one direction, said axis of swinging movement of the strips being substantially perpendicular to the 90 planes of the opposed edges of the strips.
- 85 14. Apparatus of the character described comprising a clamp composed of opposed strips pivotally connected at one end to permit swinging movement about a common axis, means at opposite ends of the strips to afford relative adjustment thereof, resilient means on the opposed edges of the strips, brackets supported on the clamps, a spindle 95 having a rotatable end, the spindle and rotatable end resting respectively in the brackets, and means within the spindle to limit rotation of the end in one direction, said axis of swinging movement of the strips being substantially perpendicular to the 100 planes of the opposed edges of the strips.
- 95 15. Apparatus of the character described comprising a clamp composed of opposed strips pivotally connected at one end to permit swinging movement about a common axis, means at opposite ends of the strips to afford relative adjustment thereof, resilient means on the opposed edges of the strips, brackets supported on the clamps, a spindle 105 having a rotatable end, the spindle and rotatable end resting respectively in the brackets, and means within the spindle to limit rotation of the end in one direction, said axis of swinging movement of the strips being substantially perpendicular to the 110 planes of the opposed edges of the strips.
- 105 16. Apparatus of the character described comprising a clamp composed of opposed strips pivotally connected at one end to permit swinging movement about a common axis, means at opposite ends of the strips to afford relative adjustment thereof, resilient means on the opposed edges of the strips, brackets supported on the clamps, a spindle 115 having a rotatable end, the spindle and rotatable end resting respectively in the brackets, and means within the spindle to limit rotation of the end in one direction, including a collar secured to the spindle, 120 said axis of swinging movement of the strips being substantially perpendicular to the planes of the opposed edges of the strips.
- 115 17. Apparatus of the character described comprising a clamp composed of opposed strips pivotally connected at one end to permit swinging movement about a common axis, means at opposite ends of the strips to afford relative adjustment thereof, resilient means on the opposed edges of the strips, brackets supported on the clamps, a spindle 125 having a rotatable end, the spindle and rotatable end resting respectively in the brackets, and means within the spindle to limit rotation of the end in one direction, including a collar secured to the spindle, 130 said axis of swinging movement of the strips being substantially perpendicular to the planes of the opposed edges of the strips.

ratchet teeth on the collar and rotatable end,
and a spring to hold the ratchet teeth in en-
gagement, said axis of swinging movement
of the strips being substantially perpendicu-
lar to the planes of the opposed edges of the
strips.

5 In testimony whereof I affix my signa-
ture.

HARRY BONAT.
